UNITED STATES PATENT OFFICE

140,099

DESIGN FOR A CEMENT PLATE FOR BUILDING WALLS

Bernice De Lores Ladwig, Marietta, Minn.

Application April 26, 1944, Serial No. 113,382

Term of patent 14 years

(Cl. D18—2)

To all whom it may concern:

Be it known that I, Bernice De Lores Ladwig, a citizen of the United States, residing at Marietta, in the county of Lac qui Parle and State of Minnesota, have invented a new, original, and ornamental Design for a Cement Plate for Building Walls, of which the following is a specification, reference being had to the accompanying drawing, forming a part thereof.

The figure is a perspective view of the cement plate showing my new design.

I claim:

The ornamental design for a cement plate for building walls, as shown.

BERNICE DE LORES LADWIG.
